GEORGE COCKSTETTER, OF CANTON, OHIO

LOCK FOR LIGHT BULBS

Application filed November 5, 1932. Serial No. 641,486.

The invention relates to means for locking an incandescent light bulb in a socket so as to prevent removal of the bulb by an unauthorized person.

Considerable expense and annoyance is caused by the theft of incandescent light bulbs from the sockets in large factories, amusement resorts, public buildings and other places where a large number of electric lights are used, making it necessary for those in charge to continually replace the stolen bulbs; and the object of the present improvement is to provide means for effectively locking a light bulb when it is screwed into a socket so as to prevent its removal by an unauthorized person.

A further object is to provide such a lock with means whereby an authorized person with the proper tools may remove the bulb from the socket in order that bulbs which have burned out may be replaced.

A still further object of the improvement is to provide a very simple and inexpensive locking device which may be quickly and readily applied to sockets of usual and ordinary construction.

The above and other objects may be attained by providing a locking ring which may be formed of two connected layers of paper or other suitable material having a fine wire, thread or other suitable flexible coil or rip cord located between the layers and adapted to be pulled out to separate said layers when it is desired to remove the bulb.

The outer surface of the locking ring is adapted to be cemented within the mouth of the lamp socket and suitable adhesive material is placed upon the inner surface of the ring which contacts with the base of the light bulb so that when the bulb is screwed into the socket, the cement or other adhesive will hold the bulb against removal therefrom.

The flexible coil of wire or thread is provided for the purpose of removing the bulb from the socket by an authorized person, with the use of a suitable tool.

An embodiment of the invention is illus-

trated in the accompanying drawing, in which Figure 1 is an enlarged sectional view through a lamp socket of usual construction showing the base of a light bulb located therein, the improved locking ring to which the invention pertains being shown applied thereto;

Fig. 2, an elevation of a lamp bulb located in a socket shown in section, the locking ring to which the invention pertains being shown in elevation;

Fig. 3, an elevation of a partly completed locking ring showing the inner layer of paper with the flexible coil thereon;

Fig. 4, a similar view showing the outer layer of paper applied over the coil and inner layer, a part being broken in section for the purpose of illustration;

Fig. 5, a similar view of the completed locking ring;

Fig. 6, a view similar to Fig. 5 of a slightly modified form of locking ring;

Fig. 7, a detached perspective view of the improved locking ring; and

Fig. 8, an enlarged sectional view through a slightly modified form of lamp socket with a modified form of locking ring located therein.

Similar numerals refer to similar parts throughout the drawing.

The improved locking ring may be formed of material suitable for withstanding the temperature to which an electric light base and socket are subjected, asbestos paper being an example of material well adapted for this purpose.

In forming the ring, a layer of the paper, indicated at 10, is located around a suitable mandrel or the like and a strand of fine wire, thread or other suitable flexible material is coiled around the layer of paper, as indicated generally at 11, a suitable adhesive material such as cement, glue or the like is then applied to the outer surface of the paper 10 and an outer layer of paper 12 is placed over the same, the completed ring thus comprising two layers of paper cemented together with the coil of wire or thread located between the layers.

The ring thus produced may then be by suitable adhesive material to both the shaped in any suitable forming device to both the socket and the lamp base. the finished form, as best shown in Figs. 5, 6 and 7 to conform to the screw threads 5 within the usual lamp socket. If desired, an annular shoulder or flange 13 may be formed at the lower edge of the ring to limit the insertion of the locking ring into the lamp socket. If desired, the upper edge 10 of the ring may be tapered, as indicated at 14 in Figs. 1 and 5, in order to facilitate the insertion of the lamp base into the socket.

The improved locking ring is adapted for use in connection with any usual and well 15 known type of lamp socket having the screw threaded sheet metal shell 15 shown in Figs. 1 and 2. In order to more easily accommodate the locking ring, the outer end portion of this sheet metal shell may be slightly 20 expanded, as indicated at 16 in Figs. 1 and 2. This may be accomplished by the use of a simple expanding tool without removing the sheet metal shell from the socket.

Both the outer and inner side walls of the 25 improved locking ring may be coated with a suitable adhesive adapted to be moistened for use in the manner of an envelope flap or a postage stamp. In applying the locking ring to the lamp socket in order to lock the 30 light bulb therein, the outer surface of the locking ring may be moistened to soften the adhesive coating thereon and the ring is screwed into the open end of the threaded sheet metal shell 15 of the lamp socket, the 35 flanged shoulder 13 upon the ring contacting with the end of said shell and limiting the movement of the ring therein.

Instead of using the adhesive coating upon 40 the outer surface of the ring and moistening the same before the ring is screwed into the shell of the socket, it should be understood that any suitable adhesive may be applied to the exterior of the ring just prior to the insertion of the ring into the 45 socket.

The lower or outer portion of the screw 50 threaded base 17 of the incandescent bulb 18 may then be moistened and the base of the bulb is then screwed into the socket in the usual manner, the moistened portion thereof being positioned within the locking ring and sufficiently moistening the adhesive coating upon the inner surface of the ring to cause the inner surface of the ring to adhere 55 to the lamp base in the same manner that the outer surface of the ring adheres to the socket.

Instead of using this particular kind of 60 adhesive coating upon the inner surface of the ring, it should be understood that any suitable cement, glue or other adhesive may be applied to the portion of the lamp base which comes to rest within the ring, the object merely being to attach the locking ring 65

In order to facilitate the removal of the lamp bulb from the socket by an authorized person, the lower or outer end of the coil 70 11 of wire, thread or the like may be extended through the lower edge of the locking ring, as indicated at 19, and an eye or loop 20 may be formed therein to be engaged by a suitable hooked instrument by 75 means of which the end of the coil of wire or thread may be more readily pulled downward and outward.

By continuing to pull this wire or thread 80 outward, it will be seen that the bond between the two sheets of paper 10 and 12 which form the ring will be broken and the two sheets of paper separated, permitting the bulb to be unscrewed in the usual manner. The paper which may adhere to the 85 interior of the socket after the light bulb has been removed may be easily scraped therefrom by any sharp edged tool.

For the purpose of entirely closing the end 90 of the socket so as to completely cover the locking ring, a washer 21 which may be formed of fiber, cardboard or any other suitable material, may be located around the lamp base, as best shown in Fig. 1, seating 95 against the outwardly flared end 22 of the base within which the upper end of the lamp bulb 18 is located.

In order to remove the lamp bulb it is first necessary to cut away this washer before 100 the proper tool is inserted into the socket to loosen the end of the coil of wire or thread and pull the same out. For complete safety the handle of this tool, as well 105 as any tool used for scraping the paper from the interior of the socket after the bulb has been removed, should be insulated in order to prevent any possibility of the operator receiving an electric shock.

A modification of the invention is shown 110 in Fig. 8 in which a special lamp socket is required. This lamp socket may be the same as the ordinary socket excepting that the screw threaded sheet metal shell 15a is provided at its outer open end with an enlarged 115 shouldered portion 23 which may be screw threaded, as indicated at 24, the threads being of much finer pitch than the threads upon the portion 15a and preferably being left-hand threads.

The locking ring provided for this form 120 of the invention may comprise a threaded sheet metal ring 25 adapted to be screwed into the threads 24 and having therein the spaced paper layers 10a and 12a between 125 which is located the coil 11a of wire, thread or the like, as above described. The outer layer 12a of paper is glued or cemented to the sheet metal ring 25.

In using this type of locking ring to lock 130 the lamp bulb in the socket, the sheet metal

ring 25, with the paper and wire or thread coil carried thereby is first screwed into the socket in the position shown in Fig. 8, after which the lamp bulb is inserted into the 5 socket as above described in the other form of the invention, the base of the lamp bulb being cemented or glued to the inner surface of the paper layer 10a in the manner above described.

10 It will be seen that any attempt to unscrew the lamp bulb will cause the locking ring to be rotated, tightening the same within the threads 24 so that it acts as a jam nut. In order to remove the lamp bulb, the wire 15 or thread coil is pulled out in the manner above described, breaking the bond between the two layers of paper 10a and 12a where by the lamp bulb may be unscrewed from the socket, after which the sheet metal ring 20 25, with the outer layer 12a adhering thereto may be unscrewed from the socket.

In order to assist in removing this screw threaded ring one or more lugs 26 may be formed upon the lower edge thereof for engagement by pliers or other suitable tool. A washer such as shown at 21 in Figs. 1 and 25 20 may be used in this form of the invention in the manner above described.

I claim:

30 1. In combination with a lamp socket and a lamp bulb having a base fitting within said socket, a locking ring located within the socket and around the base and comprising two layers of paper and the like connected together by an adhesive and a coil of wire and the like located between said layers, said locking ring being connected to the socket and the base.

2. In combination with a lamp socket and 40 a lamp bulb having a base fitting within said socket, a locking ring located within the socket and around the base and comprising two layers of paper and the like connected together by an adhesive and a coil of wire and the like located between said layers, said locking ring being connected to the socket and the base, one end of said coil protruding through the outer edge of said locking ring.

50 3. In combination with a lamp socket and a lamp bulb having a base fitting within said socket, a locking ring located within the socket and around the base and comprising two layers of paper and the like connected together by an adhesive and a coil of wire and the like located between said layers, said locking ring being connected to the socket and the base, one end of said coil protruding through the outer edge of said locking ring and having a loop formed therein.

4. In combination with a lamp socket and a lamp bulb having a base fitting within said socket, a locking ring located within the 60 65 socket and around the base and comprising

two layers of paper and the like connected together by an adhesive and a coil of wire and the like located between said layers, said locking ring being connected to the socket and the base, the outer edge of said 70 ring having an annular shoulder adapted to contact with the outer edge of the socket.

5. In combination with a lamp socket and a lamp bulb having a base fitting within said socket, a locking ring located within the socket and around the base and comprising two layers of paper and the like connected together by an adhesive and a coil of wire and the like located between said layers, said locking ring being connected to the socket and the base, the inner edge of 75 80 85 said ring being tapered.

6. In combination with a lamp socket and a lamp bulb having a base fitting within said socket, a locking ring located within the socket and around the base and comprising two layers of paper and the like connected together by an adhesive and a coil of wire and the like located between said layers, said locking ring being connected to the socket and the base, the inner edge of 90 95 100 said ring being tapered and the outer edge of the ring having an annular shoulder adapted to contact with the outer edge of the socket.

7. As an article of manufacture, a locking ring for locking the base of a light bulb in a lamp socket, said ring including two layers of paper and the like connected together by an adhesive and a coil of wire and the like located between said layers, the ring being adapted to surround the lamp base within the socket and to be connected to the base and socket.

8. As an article of manufacture, a locking ring for locking the base of a light bulb in a lamp socket, said ring including two layers of paper and the like connected together by an adhesive, a coil of wire and the like located between said layers, and a ring of sheet metal and the like connected to the outer layer of said paper and adapted to be connected to the interior of the socket, the inner layer of paper being adapted to be connected to the lamp base.

9. As an article of manufacture, a locking ring for locking the base of a light bulb in a lamp socket, said ring including two layers of paper and the like connected together by an adhesive, a coil of wire and the like located between said layers, and a screw threaded ring of sheet metal and the like connected to the outer layer of said paper and adapted to be connected to the interior of the socket, the inner layer of paper being adapted to be connected to the lamp base.

10. In combination with a lamp socket having a screw threaded shell provided with an enlarged open end having screw threads of relatively fine pitch, and a lamp bulb hav-

ing a base threaded to fit said shell, a locking ring including two layers of paper and the like connected together by an adhesive, a coil of wire and the like located between said layers, and a screw threaded ring of metal and the like connected to the outer layer of paper and adapted to be threaded into the enlarged end of said shell, the inner layer of paper being adapted to be connected to the lamp base.

11. In combination with a lamp socket having a screw threaded shell provided with an enlarged open end having oppositely disposed screw threads, and a lamp bulb having a base threaded to fit said shell, a locking ring including two layers of paper and the like connected together by an adhesive, a coil of wire and the like located between said layers, and a screw threaded ring of metal and the like connected to the outer layer of paper and adapted to be threaded into the enlarged end of said shell, the inner layer of paper being adapted to be connected to the lamp base.

25

12. In combination with a lamp socket having a screw threaded shell provided with an enlarged open end having oppositely disposed screw threads of relatively fine pitch, and a lamp bulb having a base threaded to fit said shell, a locking ring including two layers of paper and the like connected together by an adhesive, a coil of wire and the like located between said layers, and a screw threaded ring of metal and the like connected to the outer layer of paper and adapted to be connected to the lamp base.

13. As an article of manufacture, a locking ring for locking the base of a light bulb in a lamp socket, said ring including two layers of paper and the like connected together and having a flexible rip cord located between said layers, the ring being adapted to surround the lamp base within the socket and to be connected to the base and socket.
